W. J. LEVERIDGE.
VACUUM TUBE HOLDER.
APPLICATION FILED AUG. 2, 1919.

1,386,714.

Patented Aug. 9, 1921.

Inventor:
Walter J. Leveridge
by *J. Roberts* Atty.

UNITED STATES PATENT OFFICE.

WALTER J. LEVERIDGE, OF MOUNT VERNON, NEW YORK, ASSIGNOR TO WESTERN ELECTRIC COMPANY, INCORPORATED, OF NEW YORK, N. Y., A CORPORATION OF NEW YORK.

VACUUM-TUBE HOLDER.

1,386,714.

Specification of Letters Patent. Patented Aug. 9, 1921.

Application filed August 2, 1919. Serial No. 314,911.

To all whom it may concern

Be it known that I, WALTER J. LEVERIDGE, a subject of the King of Great Britain, residing at Mount Vernon, in the county of 5 Westchester, State of New York, have invented certain new and useful Improvements in Vacuum-Tube Holders, of which the following is a full, clear, concise, and exact description.

10 This invention relates to vacuum tubes and more particularly it relates to a holder for such tubes.

15 In the manufacture of vacuum tubes, particularly of the type comprising more than one electrode, it has been found convenient to subject the electrodes of the tubes to electrical tests previous to the final mounting of the glass tube in its collar or shell on which are provided terminal lugs for the 20 lead-in wires of the various electrodes of the tube.

25 An object of the invention is to provide a holder for unmounted vacuum tubes so that they may readily be connected in a circuit for any electrical tests desired.

30 The holder provided according to this invention comprises in its preferred form a block preferably of insulating material, on one side of which is a collar on which are 35 mounted terminal lugs which are adapted to coöperate with spring clips or other form of contacts in a base or socket adapted to receive the collar. Preferably there should be as many lugs as there are lead-in wires 40 for the vessel to be held. On the other side of the block are mounted a plurality of spring clips between which the glass bulb may be securely held. Projecting from the same side of the block are a plurality of 45 binding posts which are of a sufficient length to enable the lead-in wires of the tube to be readily and conveniently fastened thereto. Each post is electrically connected to one of the lugs mounted on the collar. 50 When, therefore, it is desired to test an unmounted vacuum tube, the tube is inserted between the spring clips and each lead-in wire is fastened to the proper binding post. The collar may then be inserted in a suitable socket which is connected to the electrical apparatus necessary to perform the testing.

This invention will be better understood by reference to the following detailed de-

scription taken in connection with the accompanying drawing which represents the preferred form of this invention.

55 Referring to the drawing, 5 is a block of insulating material on one side of which are mounted a plurality of spring clips 6, 7, 8 and 9, which are adapted to hold securely the glass bulb 10 of a vacuum tube. Projecting from the block 5, are also a plurality of binding posts 12, 13, 14 and 15, each of which is provided with a spring 17 and a washer 18, whereby the lead-in wires may be electrically connected to the binding posts in a convenient manner.

60 Mounted on the opposite side of block 5 is a collar 25 from which project the terminal lugs 26, 27, 28, 29. Each of these lugs is electrically connected to one of the binding posts by electrical connections located in the grooves 30 in the top of block 5. The collar 25 which is preferably of the 65 type used on the vacuum tubes designed to be held by the spring clips of the holder, is adapted to be inserted in a socket which contains spring clips or other form of contacts which are adapted to coöperate with 70 the lugs 26 to 29 for providing electrical connections between the electrodes of the tube 10 and the testing apparatus. One form of socket with which collar 25 is 75 adapted to coöperate is described and claimed in a pending application to Shreeve, Serial No. 98,770, filed May 20, 1916.

80 The form of vacuum tube collar shown for this holder is not a part of this invention but is the invention of another and is described and claimed in a patent application to Shreeve, Serial No. 218,254, filed February 20, 1918.

85 It is to be understood that the vacuum tube holder of this invention is not limited 90 to the particular form described above, but it may be variously modified without departing in any wise from the spirit of this invention as defined in the appended claims.

95 What is claimed is:

1. A holder for a vacuum tube comprising a block, means for holding said vacuum tube, binding posts on said block, and terminal lugs on said block electrically connected to said binding posts. 100
2. A holder for a vacuum tube comprising a block, spring tube-engaging fingers on said block, binding posts on said block, and 105

- terminal lugs on said block electrically connected to said binding posts.
3. A holder for a vacuum tube comprising a block, spring tube-engaging fingers projecting from said block, binding posts projecting from said block in the same direction as said fingers, and terminal connections for said holder on the side of said block opposite said fingers, said terminal connections being electrically connected to said binding posts.
4. A holder for a vacuum tube comprising a block, spring tube-engaging fingers projecting from said block, binding posts projecting from said block in the same direction as said fingers, a vacuum tube collar on the side of said block opposite said fingers, and terminal connections for said holder comprising a plurality of lugs projecting from said collar, said lugs being electrically connected to said posts.
5. A holder for a vacuum tube comprising a block, spring tube-engaging fingers projecting from said block, binding posts projecting from said block in the same direction as said fingers and corresponding in number to the number of lead-in wires possessed by the tube to be held, a collar on the side of said block opposite said fingers, and terminal connections for said holder comprising a plurality of lugs projecting from
- said collar, said lugs being directly connected to said binding posts and corresponding in number to the number of lead-in wires possessed by the tube to be held.
6. A holder for a vacuum tube comprising a block of insulating material, spring tube-engaging fingers projecting from said block, binding posts projecting from said block in the same direction as said fingers and corresponding in number to the number of lead-in wires possessed by the tube to be held, wire-fastening means on the ends of said posts, a vacuum tube collar on the side of said block opposite said fingers, terminal connections for said holder comprising a plurality of lugs projecting from said collar, and an electrical connection between each of said lugs and one of said binding posts, said lugs corresponding in number to the number of lead-in wires possessed by the tube to be held.
7. A holder for a vacuum tube comprising terminal lugs, members contacting with said tube for positioning said tube with respect to said lugs, and a plurality of rigid electrical connectors extending from points adjacent the base of said tube in the direction of said lugs.

In witness whereof, I hereunto subscribe my name this 28th day of July, A. D. 1919.

WALTER J. LEVERIDGE.
